LUMINAIRE

Eldon L. Anderson, Jr., Fletcher, N.C., assignor to General Electric Company

Filed June 1, 1970, Ser. No. 33,218

Term of patent 14 years

Int. Cl. D26—05

U.S. Cl. D48—23

FIG. 1 is a top plan view of a luminaire embodying my new design;

FIG. 2 is an elevational view thereof; and
FIG. 3 is a bottom plan view thereof.

I claim:

The ornamental design for a luminaire, as shown.
